MAGAZINE RAZOR

Samuel C. Stampleman, Cohasset, and Joseph Muros, Cambridge, Mass., assignors to Gillette Safety Razor Company, Boston, Mass., a corporation of Delaware

Application December 14, 1939, Serial No. 309,218

8 Claims. (Cl. 30—40)

This invention relates to safety razors of the magazine type and consists in improvements in structure and operation which result in greater accuracy, reliability, freedom from jamming and general convenience to the operator than has been found in implements of this class heretofore available. It also results in a simplified mechanism which may be manufactured and assembled to good advantage in quantity production.

An important feature of the invention consists in a one-piece detachable blade-retaining member which is made of resilient material and shaped to the contour of the razor head so that it may be assembled by being sprung upon the head and thus held in position as part of the razor assembly. Besides eliminating the necessity for fastening devices, this construction greatly facilitates the assembling operation and thus reduces the cost of the razor.

Another feature of the invention consists in a blade locating or positioning member of spring material presenting blade stops at opposite ends of the stationary guard which are effective to position the blade accurately upon the blade seat of the razor. These stops may be conveniently retracted to release the blade by the presentation of the magazine holder when it is desired to replace the blade.

These and other features of the invention will be best understood and appreciated from the following description of a preferred embodiment thereof, selected for purposes of illustration and shown in the accompanying drawings, in which:

Fig. 1 is a view in side elevation of the razor head;

Fig. 2 is a similar view in front elevation;

Fig. 3 is a sectional view on an enlarged scale of the razor head;

Fig. 4 is a view of the razor head in front elevation showing the razor tilted at a different angle from that of Fig. 2;

Fig. 5 is a plan view of the holder and magazine;

Figs. 6 and 7 are similar views showing the razor and magazine holder partially and fully connected, in Fig. 7 the magazine being shown in the forward position it occupies at the conclusion of its blade-delivering stroke;

Fig. 8 is a view in perspective of the blade positioning or locating member of the razor;

Figs. 9, 10 and 11 are plan views of the holder with the magazine in different positions thereon;

Fig. 12 is a view in elevation of the magazine holder;

Fig. 13 is a view in elevation of the magazine;

Fig. 14 is a view on an enlarged scale of the magazine holder partly in elevation and partly in section;

Fig. 15 is a view in perspective on an enlarged scale of the magazine showing part of its wall as broken away.

The razor herein shown is designed to take a flat single-edged blade 30 of the type shown in Figs. 7, 11 and 15, that is to say, a narrow rectangular blade having end notches 31 and spaced rectangular apertures 32 and 33 in its body. The razor itself comprises a handle 10 threaded at its upper end into a solid head 11 which may be die-cast or otherwise fashioned and which includes as an integral part thereof an outwardly or forwardly projecting flange 12 provided at its inner edge with a longitudinal shoulder and constituting a flat elongated blade seat in the razor. The body of the head 11 is elongated transversely and rounded at its upper and lower rear edges and its flange portion 12 is extended forwardly and downwardly beyond the blade seat and serrated to form a stationary guard 13 which, in the assembled razor, is disposed beneath the shaving edge of the blade. A spring retaining or hold-down member 14 is curved to conform to the contour of the head 11 and provided with a flat forwardly extending flange which co-operates with the blade seat to hold the blade 30 in place by yieldingly engaging the same. The hold-down member 14 may be forceably sprung out of engagement with the head 11 but otherwise it remains in contact with the head as a permanent part of the razor assembly and its blade-engaging flange is separated from the blade seat only sufficiently to permit a blade to be forced yieldingly beneath it in endwise direction.

Yielding blade positioning or locating stops co-operate with the blade seat and with the shoulder constituting its inner boundary to retain the back of the blade in contact with that shoulder and thus to position its shaving edge properly and safely with respect to the fixed guard 13. To this end, the ends of the guard 13 are notched and the front and lower faces of the head 11 are recessed to receive a forked member 15 of resilient sheet metal. This member, as best shown in Fig. 8, comprises a base flange 34 which is perforated for the passage of the threaded stem of the handle 10 and shaped to fit into the corresponding recess provided in the under face of the head 11. The base flange 34 of the member 15 merges into an upstanding portion which fills a wide shallow recess bounded by diverging end wall provided for that purpose in the front

face of the head 11 as shown in Fig. 2. This up-standing portion of the member 15 merges in turn into a pair of diverging arms terminating in the upstanding blade-engaging stops 16. These stops are so located as to embrace the guard 13, engage the outer corners of the blade edge and normally press the blade inwardly to maintain its back edge in contact with the shoulder of the blade seat 12. The main or center portion of the member 15 as shown in Fig. 8 is bent inwardly to form a substantially horizontal angular arm 17 having a down-turned wall or flange 29 providing a contact face disposed midway between the blade stops 16 and substantially in alignment and above the perforation in the base flange 34 of the member.

The head 11 is provided with a straight shouldered channel or passage 18 extending longitudinally through it from side to side and disposed substantially at right angles to the blade seat. The front wall of the head is cut-out centrally providing an opening or transverse passage to receive the arm 17 of the spring blade-retaining member and permit its oblique wall 29 to stand in the channel 18 as shown in Figs. 1 and 3; that is, the internal transverse passage extends from the longitudinal passage 18 and opens into the front face of the head, being covered by the member 15. As will be presently described the forked blade retaining member may be sprung forwardly to release the blade by a prying member forced into the channel 18. It will be understood that the blade seat provided by the flange 12 is open at both ends and that a blade may be presented in shaving position by being introduced endwise into the razor beneath the yielding flange of the hold-down member 14 while the blade stops 16 are temporarily retracted or moved away from the inner shoulder of the blade seat. The member 15 may be formed by bending a sheet metal blank and in assembling the razor it is necessary only to drop it into the recess provided for it in the head, pass the threaded stem of the handle through the perforation in its flange and tighten the handle. The razor thus far described is a complete shaving implement and does not require a blade magazine although it is most effectively employed in co-operation with such a magazine.

The magazine mechanism herein disclosed includes a holder, best shown in Figs. 12 and 14, and comprising an elongated sheet metal member having a flat guideway 20 defined by parallel inturned edge flanges 21 and 22. The rear end of the guideway is closed by spring detent 23 which may be temporarily depressed below the level of the guideway, as shown in Fig. 14, when it is desired to introduce or remove the magazine but which otherwise prevents accidental disengagement of the magazine. The guideway is formed integral with a projecting finger 24 which is parallel to the guideway but disposed in edgewise relation thereto. The finger 24 has a bevelled end and is shaped to enter the channel 18 of the razor, being sufficiently long to locate the holder positively with its guideway in registration with the blade seat provided by the flange 12 of the razor head. The finger 24 is provided on one face with an elongated rib 25 which travels in the reduced portion of the channel when the finger is inserted therein and is the part of the finger which comes in actual contact with the oblique face 29 of the stop controlling arm 17 already referred to. The finger 24 is also provided in its lower edge with a shoulder 26 which engages the end face of the head 11 and to deter-

mine the endwise position of the holder when operatively connected to the razor head. The bottom of the holder is provided with a pair of rectangular openings through which project spring detents 27 and 28, one located in advance of the other. A short section 19 of the flange 22 is separated from the rest of the flange and pressed together to form a solid stop for limiting movement of the magazine toward the left.

The magazine itself comprises a rectangular box 40 of sheet metal having at its one open side a pair of spaced parallel flanges 41 made by folding the sheet material of the magazine so that it presents two outwardly extending ribs, shaped to run beneath the inturned flanges 21 and 22 of the guideway of the holder, and two inturned blade confining ribs. The inner edges of the flanges 41 are spaced apart so as to expose the center section of the lowermost blade in the magazine with its apertures 32 and 33. The flanges 41 are slightly shorter than the full length of the magazine thus leaving short open spaces adjacent to the front and rear walls thereof. Both the end walls of the magazine are provided with inwardly projecting vertical ribs 35 shaped to fit the end notches 31 of the blades and thus to hold the sharp edge thereof out of contact with the wall of the magazine and prevent them from being dulled when discharged. The front end wall of the magazine is provided with a spring feed dog 42 which normally projects forwardly and downwardly and is adapted to engage the inner aperture 33 of the lowermost blade in the magazine as will be presently described. Within 30 the magazine is provided a leaf spring 43. This is riveted to the top of the magazine and arranged to press downwardly upon the blade stack contained therein, holding the lowermost blade always in contact with the flanges 41. The magazine may be loaded by inserting blades from either 35 end above the flanges 41, meanwhile pressing them inwardly to deflect the leaf spring 43.

When it is desired to replace a blade in the safety razor with the assistance of the magazine mechanism above described the holder is brought into the relation with respect to the razor as suggested in Figs. 4 and 5, that is to say, the finger 24 is aligned with the shouldered channel 18. The finger 24 is then introduced into the channel, as shown in Fig. 6, and the holder is moved to the left until arrested by engagement of the shoulder 26 with the right-hand wall of the razor head, as shown in Fig. 7. In this movement, the rib 25 on the finger engages and outwardly displaces the stop controlling arm 17, springing the member 15 outwardly and moving the blade stops 16 forwardly as indicated in Fig. 7 so that the blade 30 is held in place upon the blade seat only by the yielding engagement with the retaining member 14.

The magazine 40 is now reciprocated in the guideway 20 from right to left and back again from left to right. In the movement of the magazine toward the right the forward detent 27 engages the forward aperture 32 of the lowermost blade in the stack and holds it stationary as the magazine completes its movement back to its rear or right-hand position. In this position, moreover, the feed dog 42 is brought into registration with the rearmost aperture 33 of that blade, all as represented in Fig. 9 of the drawings. The magazine is now moved again toward the left and the blade 30 is advanced by the feed dog 42 out of the guideway 20 and into the razor 70 for about one-half its length, displacing the used

blade by pushing it ahead and partially out from the left-hand side of the razor. The magazine is shown in this condition in Fig. 10. The magazine is now moved again toward the right, as best shown in Fig. 11 leaving the blade half exposed in the guideway 20 and half inserted into the razor. In this movement of the magazine the blade is held stationary in the guideway 20 by the rearmost detent 28 in the bottom of the guideway which engages the rear end of the blade. Finally the magazine is moved again toward the left and in this movement the blade which is lowermost in the magazine acts to advance the half exposed blade pushing it fully into the razor, locating it in shaving position and fully ejecting the used blade. The holder is then detached by withdrawing the finger 24, whereupon the stop controlling arm 17 is released by the rib 25 and the blade stops 16 move inwardly engaging the corners of the blade and seating it accurately upon the blade seat, ready for shaving.

From the foregoing description it will be apparent that the magazine holder with a magazine of blades may be easily connected to the razor or detached therefrom at the option of the user and that when the holder has been so attached a new blade may be presented in shaving position by imparting two complete reciprocations to the magazine in the holder. The first reciprocation inserts the new blade half-way into the razor where it is held securely in place by engagement with it of the retaining member 14 and also by the detent 28. The blade therefore is secured against displacement during the first half of the second reciprocation of the magazine. In the final movement in this second reciprocation of the magazine the new blade is fully seated and the old blade fully ejected. Blades may be supplied in this manner as long as the supply holds out in the magazine. When the magazine is exhausted it may be removed from the holder by depressing the detent 23, thus permitting the magazine to be drawn out of the guideway 20. The magazine may be then conveniently refilled or if the blades are dispensed in the magazine a new full magazine may be slipped into the guideway.

Having thus disclosed our invention and described a preferred embodiment thereof for purposes of illustration but not in any limiting sense, We claim as new and desire to secure by Letters Patent:

1. A safety razor having a head with a passage therein and presenting a blade seat extended to form an integral guard, a spring sheet metal member having its body secured to the head at a point substantially below the blade seat and shaped to present a blade stop at either end of the guard and a position-controlling arm which extends into the passage in the head where it may be displaced by a prying member inserted in said passage.

2. A safety razor having an elongated head with an exterior blade seat and an interior passage disposed parallel thereto in the solid material of the head, said passage communicating through an intermediate opening with one face of the head, and a resilient blade-locating member attached to the head substantially below the said passage and presenting through said intermediate opening an inclined contact face in said passage in position to be displaced by a member movably guided in said passage.

3. A safety razor having a head presenting a long flat blade seat and stationary guard and being provided with a passage enclosed by the material of the head and extending from end to end thereof, a resilient sheet metal member attached to the head substantially below the blade seat and embracing both ends of the guard, positioning the blade and provided at an intermediate point with an inwardly extending arm which reaches into the said enclosed passage in position to be displaced by a prying member inserted in said passage.

4. A safety razor having a body providing a flat blade seat, a rectangular channel disposed below and at an angle to said blade seat and an opening through one wall of the channel, in combination with movable blade stops supported at a point substantially below said channel, associated with said blade seat and having an operating arm projecting through the opening into said channel.

5. A safety razor having a body providing a flat horizontally disposed blade seat and a substantially rectangular interior passage disposed 25 edgewise with respect to the blade seat and shouldered to form a wide central zone, in combination with a spring blade retainer secured to the exterior of the head substantially below said passage and having blade stops at each end of the 30 blade seat and an operating arm standing in the wide zone of the said interior passage.

6. A safety razor having a head provided with an external blade seat, an internal longitudinal passage substantially parallel to the blade seat 35 and a transverse passage extending between said longitudinal passage and an outer face of the head, in combination with a resilient plate secured to the head substantially below the blade seat and shaped to close the outer end of said 40 transverse passage and being provided with spaced blade stops movably positioned at either end of the blade seat and with an operating arm movable in said transverse passage.

7. A safety razor having a head provided with 45 a blade seat, an internal passage substantially parallel to the blade seat and a transverse passage opening out through one face of the head and at its inner end intersecting said internal 50 passage, in combination with a resilient sheet metal plate secured to the head substantially below said passage and shaped to close the outer end of said transverse passage, having blade stops movably disposed adjacent to the ends of the 55 blade seat and an operating arm extending inwardly into said internal passage.

8. A safety razor having a transverse head presenting a flat blade seat and provided with an elongated passage disposed substantially parallel to the blade seat and located within the body of 60 the head below the blade seat and with an intersecting passage opening outwardly through one face of the head and inwardly into said elongated passage, and a resilient blade-locating member of sheet metal attached to the head substantially below the said passage and having 65 movable arms extending upwardly into proximity to the opposite ends of the blade seat to position a blade thereon and an intermediate arm extending into said elongated passage in position 70 to be displaced by an elongated member passed into the said passage.

SAMUEL C. STAMPLEMAN.
